CLAIM

The ornamental design for a fish holder as shown and described.

DESCRIPTION

FIG. 1 is a perspective view of a fish holder showing my new design;

FIG. 2 is a front plan view thereof;

FIG. 3 is a rear plan view thereof;

FIG. 4 is a top plan view thereof;

FIG. 5 is a bottom plan view thereof;

FIG. 6 is a bottom axial view thereof;

FIG. 7 is a top axial view thereof; and,

FIG. 8 is another front plan view of the fish holder shown in a use configuration with environment.

The broken lines depict environment of a fish that forms no part of the claimed design.
